UNITED STATES PATENT OFFICE.

JOHN EVANS, HERBERT GEORGE HOWITT, AND WYNDHAM JAMES PRICHARD, OF GLAMORGAN, WALES.

APPARATUS OR DEVICE FOR WINDING AND PAYING OUT FILMS, TAPES, AND THE LIKE.

1,192,776.

Specification of Letters Patent. Patented July 25, 1916.

Application filed May 16, 1914. Serial No. 839,068.

To all whom it may concern:

Be it known that we, JOHN EVANS, HERBERT GEORGE HOWITT, and WYNDHAM JAMES PRICHARD, subjects of the King of England, 5 all residing in Glamorgan, South Wales, have invented certain new and useful Improvements in Apparatus or Devices for Winding and Paying Out Films, Tapes, and the like, of which the following is a specification.

This invention relates to apparatus for winding and paying out films, tapes and the like.

The object of the present invention is to 15 devise an improved form of apparatus, particularly suitable in connection with cinematograph films, whereby the re-winding of the film or the like is entirely obviated.

Broadly the invention consists in an apparatus 20 comprising in combination a revoluble support for the film or the like and a guide for the inner convolution to guide it clear of the outer convolutions as the film or the like is unwound commencing from 25 its inner convolution.

In one preferred construction according 30 to this invention the apparatus comprises a box or receptacle hinged or pivoted upon the machine in connection with which it is to be employed, an inner revoluble member 35 adapted to support the film or the like, a series of fixed guide rollers arranged at the center of the revoluble member and guides for guiding the inner convolution of 40 the film or the like above the outer turns of the same. The box or receptacle is connected with the machine by a single hinged member so that, although normally in the horizontal position, it may be turned into 45 the vertical to facilitate the transfer of a roll of film to the spool-box when required.

The invention also consists in the provision 50 of a brake adapted to act upon the revoluble member and other details and arrangements hereinafter more particularly referred to.

The accompanying drawings illustrate one mode of carrying out the invention.

Figure 1 is a plan showing one convenient form of device constructed in accordance with the invention. Fig. 2 is a sectional elevation of the apparatus shown in Fig. 1. Fig. 3 is a front elevation showing a modified form of box. Fig. 4 is a frag-

mentary view showing in side elevation a portion of the box illustrated in Fig. 3, when looking from the right of that figure.

In carrying our invention into effect in one convenient manner as, for example, in its application to the winding and paying out 60 of cinematograph films, we provide a spool box *a* of any suitable size and form provided with a conveniently hinged or other cover *b* and having a hinged or other attachment 3 (Fig. 2) upon the lower face thereof, such 65 that the box may be readily secured to any form of projecting apparatus with which it is to be employed. Within the spool box *a* we arrange a fixed central fitting comprising a pair of plates *c* and *d* between 70 which are mounted any convenient number of rollers *e* such that their outer surfaces project slightly beyond the end plates *c* and *d* as shown in the drawings. Beneath the portion of the central fitting carrying the 75 rollers *e* we arrange a disk or other fitting *f* adapted to hold the film that is to be unwound and furnished if necessary or desirable with two flanges or rings *g* and *h* between which the film is arranged. The 80 flange *h*, as shown, extends beyond the central guide-rolls, that is, beyond them when considered in a direction away from the center of rotation and affords an annular stop or bearing-surface for the inner convolution 85 of the film and prevents the film from tightening unduly around the rolls, as by its means the film during its unwinding is enabled more readily to rotate the support *f*. The member *f* is rotatably mounted in 90 known manner within the spool box in any suitable bearings as, for example, by means of the ball bearings *i* and *k*, and the arrangement is such that after the film has been inserted within the spool box the interior free end of the film or that end at the center of the coil may be threaded between one pair of rollers as more clearly shown in Fig. 1 and led to the film exit of the box, suitable guides or the like *l* and *m* being provided to facilitate the unwinding of the film and to prevent the same from tightening on or around the center-piece as it is being pulled or fed from the box.

The entire box may be of sufficient depth 105 as shown in Fig. 2 to allow of the necessary elevation of the outgoing strip of film so that the same shall not be in danger of foul-

ing the roll of film within the box, or as shown in Figs. 3 and 4 we may provide the box with a strip or like member *n* of sufficient height to accommodate the delivery 5 rollers *o p* between which the film *q* is drawn or fed, that portion of the film upon the exterior of the box being protected if desired by means of a hinged or other suitable gate *r*, while the cover is of such form that it 10 shall completely inclose that portion of the film between the center fitting within the spool box and the delivery rollers *o p*. If desired, the box or the cover may be provided with a slot or other opening through 15 which the outgoing film may pass. A roll of film wound in any desired manner is placed in the spool box so that its inner convolution encircles the vertical guide rolls *e* and the roll as a whole is carried upon the 20 rotatable member *f*. The inner end of the film is then threaded from the rollers in the manner above referred to and led to the delivery rolls *o p*, the arrangement being such that the inner turn of the film embraces the 25 flange ring *h* as the film is being drawn through the projecting apparatus, it being obvious that the film thus passes in the direction necessary for the correct display of the picture and is once more received upon a spool 30 ready for re-transfer into the spool box when required for re-showing. In this manner re-winding of the film is entirely obviated with the result that there is a considerable saving in time and labor involved, 35 while the effective life of the film is considerably prolonged so that its value is correspondingly increased.

To prevent the member *f* from overrunning the film as the latter is being drawn 40 from the box we may provide any suitable form of brake such, for example, as that shown more clearly in Fig. 1 which consists in a spring band 1 adapted to bear upon a boss formed on the rotatable member *f* and 45 being such that it is normally out of contact with said member. As soon however as there is a tendency for the member to overrun the film, the spring brake may be brought into action by the attendant by 50 means of a movable rod 2 adapted to be screwed or otherwise moved so that it may be caused to bear upon the spring band 1 which thus exerts a braking effect upon the film-carrying member *f*.

55 The bracket or other member 3 by which the device is secured to the projecting apparatus is hinged so that the box which normally rests in the horizontal position during the paying out of the film may be turned 60 into the vertical for the purpose of assisting the operator to transfer a roll of film to the spool box when required.

It will be obvious that our invention is not to be confined to the particular details 65 of construction hereinbefore given by way

of example, nor to any particular arrangement of delivery rolls or braking apparatus that is to be employed, as these and other details may be suitably modified depending upon the type of projecting apparatus with 70 which the paying out apparatus is to be employed or any other purpose for which our invention is to be employed.

What we claim as our invention and desire to secure by Letters Patent is:—

1. Apparatus for paying out films, tapes or the like comprising in combination, a revoluble support, centrally-arranged guide-rolls rotating about fixed axes to guide the inner convolution of the film clear of the outer convolutions as it is unwound from the inner convolution, and an inner annular flange on the revoluble member which surrounds the guide-rolls, which extends within the inner convolution of the roll of film and which is of such a diameter that its outer periphery extends beyond the central guide-rolls considered in a direction away from the center of rotation.

2. Apparatus for paying out films, tapes or the like comprising in combination, a revoluble disk-like support, centrally-arranged guide-rolls rotating about fixed axes to guide the inner convolution of the film clear of the outer convolutions as it is unwound from the inner convolution, an inner annular flange on the revoluble member which surrounds the guide-rolls, which extends within the inner convolution of the roll of film and which is of such a diameter that its outer periphery extends beyond the central guide-rolls considered in a direction away from the center of rotation, and an outer flange at the outer periphery of the revoluble guide-member.

3. Apparatus for paying out films, tapes or the like comprising in combination, a revoluble disk-like support, centrally-arranged guide-rolls rotating about fixed axes to guide the inner convolution of the film clear of the outer convolutions as it is unwound from the inner convolution, an inner annular flange on the revoluble member which surrounds the guide-rolls, which extends within the inner convolution of the roll of film and which is of such a diameter that its outer periphery extends beyond the central guide-rolls considered in a direction away from the center of rotation, and a brake adapted to act upon the revoluble member to prevent 105 said member overrunning the film.

4. Apparatus for paying out films, tapes or the like comprising in combination, a revoluble disk-like support, centrally-arranged guide-rolls rotating about fixed axes to guide 110 the inner convolution of the film clear of the outer convolutions as it is unwound from the inner convolution, an inner annular flange on the revoluble member which surrounds the guide-rolls, which extends with- 115

- in the inner convolution of the roll of film and which is of such a diameter that its outer periphery extends beyond the central guide-rolls considered in a direction away from the center of rotation, an outer flange at the outer periphery of the revoluble guide-member, and a brake adapted to act upon the revoluble member to prevent said member overrunning the film. 5
- 10 5. Apparatus for paying out films, tapes and the like and comprising in combination an outer box or receptacle movably mounted on the machine in connection with which the apparatus is to be employed, an inner revoluble member adapted to support the film or the like, vertically-disposed guide-rolls rotatable about fixed axes and disposed centrally of the revoluble member, other guides for guiding the inner convolution above the outer turns of the film or the like within the box, and a brake adapted to act upon the revoluble member when required. 15
6. Apparatus for paying out films, tapes and the like comprising in combination a revoluble support for the film or the like, a plurality of vertically-disposed guide-rolls rotatable about stationary axes and disposed centrally of the revoluble support, stationary guides for guiding the inner convolution of the film or the like above the outer convolutions thereof, an outer box-like casing inclosing the revoluble support, stationary guides, a cover for said box, an aperture in a part of the inclosing casing through which the film can be paid out, an adjustable friction brake for the revoluble member to limit the speed at which it is revolved, and a support for the outer casing adapted to be secured in the machine in connection with which the apparatus is to be employed and having a hinged portion secured to the outer casing whereby the latter may be tilted from its normal position. 20
- 25 7. Apparatus for paying out films, tapes or the like comprising in combination, a revoluble disk-like support, centrally-arranged guide-rolls rotating about fixed axes to guide the inner convolution of the film, an inner annular flange on the revoluble member which surrounds the guide-rolls, which extends within the inner convolution of the roll of film and which is of such a diameter that its outer periphery extends beyond the central guide-rolls considered in a direction away from the center of rotation, an outer flange at the outer periphery of the revoluble guide-member, and a stationary inclosing casing for the device having an outlet for the removal of the film as it is being unwound from its inner convolution. 30
- 35 8. Apparatus for paying out films, tapes or the like comprising in combination, a revoluble disk-like support, centrally-arranged guide-rolls rotating about fixed axes to guide the inner convolution of the film, an inner annular flange on the revoluble member which surrounds the guide-rolls, which extends within the inner convolution of the roll of film and which is of such a diameter that its outer periphery extends beyond the central guide-rolls considered in a direction away from the center of rotation, an outer flange at the outer periphery of the revoluble guide-member, and a stationary inclosing casing for the device having an outlet for the removal of the film as it is being unwound from its inner convolution. 35
- 40 9. Apparatus for paying out films, tapes or the like comprising in combination, a revoluble support for the film or the like, a plurality of vertically-disposed guide-rolls rotatable about stationary axes and disposed centrally of the revoluble support, an inner annular flange on the revoluble member which surrounds the guide-rolls, which extends within the inner convolution of the roll of film and which is of such a diameter that its outer periphery extends beyond the central guide-rolls considered in a direction away from the center of rotation, an outer box-like casing inclosing the revoluble support and central guide-rolls and having a cover, an aperture in a part of the inclosing casing through which the film can be paid out, an adjustable friction brake for the revoluble member to limit the speed at which it is revolved and a support for the outer casing adapted to be secured in the machine in connection with which the apparatus is to be employed and having a hinge portion secured to the outer casing whereby the latter may be tilted from its normal position. 45
- 45 10. In testimony whereof we have signed our names to this specification in the presence of two subscribing witnesses.
